Application October 4, 1950, Serial No. 188,317

11 Claims. (Cl. 134—112)

1

This invention relates to dish-washing machines, and particularly to those in which the dishes to be washed are contained in a closed chamber in which a plurality of rotating spinners or spraying devices are arranged. One of the objects of the invention is to provide, in a construction of this character, a plurality of such spinners or spraying devices, arranged in groups and adapted to be selectively and intermittently rotated while spraying, and while the spinners in the other groups are rotated but are not spraying.

Another object of the invention is to provide means by which the spinners in one group will be distributing the spraying fluid while those in another group will idly rotate and not spray, and to provide means for automatically causing the sprayers in one group to cease spraying and those in the other group to begin to spray, and thus alternately cause the several sprayer groups to spray the dishes contained in the machine.

The invention further contemplates the provision of an improved valve control by means of which the washing fluid supply is delivered to one group of the spraying instrumentalities for a given period of time and is then diverted to a second group, with this sequence repeated as long as the machine is in operation, and with means provided by which the periods of spraying operation of each group of spraying devices can be varied to meet washing requirements.

These and other objects are attained by the invention, a more particular description of which will hereinafter appear and be set forth in the claims forming a part of this specification.

In the accompanying drawings, wherein an illustrative embodiment of the invention is disclosed, Fig. 1 is a front elevation of the improved dishwasher, with parts in section and other parts broken away, to disclose construction; Fig. 2 is a sectional view, taken on the line 2—2 of Fig. 1, looking in the direction of the arrows; Fig. 2A is a view similar to Fig. 1 with the hinged front removed to illustrate both the top and bottom spraying devices; Fig. 3 is a sectional view in plan, of a modified structure; Fig. 4 is a sectional view of the automatic valve included as a part of the dishwasher mechanism; Fig. 5 is a sectional view, taken on the line 5—5 of Fig. 4, looking in the direction of the arrows; Fig. 6 is a sectional view, taken on the line 6—6 of Fig. 5, looking in the direction of the arrows; Fig. 7 is a sectional view of a portion of the mechanism shown in Fig. 6; Fig. 8 is a top plan view of the device shown in Fig. 7; Fig. 9 is a

2

longitudinal sectional view through a modified form of valve, the view being taken on the line 9—9 of Fig. 11; Fig. 10 is a side elevational view of the valve shown in Fig. 9; Fig. 11 is a sectional view, taken on the line 11—11 of Fig. 10, looking in the direction of the arrows; and Fig. 12 is a sectional view, taken on the line 12—12 of Fig. 10, looking in the direction of the arrows.

Referring to the structure illustrated in Figs. 10 to 3 inclusive, 10 designates the housing or casing of a dishwashing machine of a type and structure adapted for attachment to a wall or other suitable support. Such housing or casing 10 includes a hinged front door 11 pivotally attached to the housing by means of the hinges 12. Contained within the housing is a dishrack or wire basket 13 in which the dishes to be washed are placed, and located below this basket or rack, and near the bottom 15 of the housing 10 is a screen 14. A similar screen, not shown, may be employed in the housing near the top or roof 16 of the housing.

Located below the lower screen 14 is a pair of rotatively-mounted spraying or rinsing devices, sometimes referred to in this art as "spinners," each of which is generally indicated at 17. Each spraying or rinsing device or spinner 17 consists of a three-arm spider 18 having a jet head 19 located centrally or axially of the spider. Both the spider 18 and the jet head 19 are together rotatively mounted on a vertical axis in a bearing member 20, the bearing members for the lower spraying or rinsing device being securely attached to the bottom 15 of the housing, on the outside of the same, and the bearings 20 for the upper spraying devices 17 being similarly securely fastened to the top or roof 16 of the housing 10.

Each of the bearing members 20 is provided with supply passages for the washing and rinsing liquids, such passages being connected to pipes 21, 22, 23 and 24 which extend from a valve generally indicated at 25 which is connected to a suitable source of water or other washing liquid, by the pipe indicated at 26. Each arm 27 of each spider 18 is provided with channeled or serrated areas 28 which cooperate with liquid jets discharged from the jet heads.

The rotatable jet heads 19 have a plurality of openings (not shown) for discharging the liquid jets therefrom, and the arms 27 serve as jet deflecting means angularly movable relative to the jet heads 19 and about the axes of the latter for changing the direction of the jets. Accordingly, each of the arms 27 is formed with a series

of serrations or grooves diagrammatically indicated at 28 which serve to change the direction of the jets in a multiplicity of directions, the arms being movable by the impact forces of the jets on the arms. The spraying devices are shown and described in my application Serial No. 740,585, filed April 10, 1947, and, if desired, reference may be had thereto for a detailed description of the spraying devices.

The hub or central part of each of the spiders 18 is provided with a pulley 29 formed on or attached to the hub thereof and by means of which the two pairs of rinsing or spraying devices 17, located at the top and bottom respectively of the housing 10, are rotated, the devices in each pair being connected by the drive belt 30. As seen in Fig. 2, the drive belt 30 is crossed in order to drive the two spraying or rinsing devices 17 in opposite directions. As an alternative, the two spraying or rinsing devices in each pair may have their arms curved in opposite directions, in which event the drive belt need not be arranged in crossed position. As a substitute for the belt drive above described, suitable gearing may be employed for effecting rotation of the spraying means.

In the modified embodiment of the invention shown in Fig. 3, each of the rinsing or spraying devices consists of a straight pipe or tube 31 having a plurality of jet openings 32. In this embodiment, the belt need not be crossed, and the jet openings 32 in the pipes or tubes 31 can be arranged angularly or obliquely so that the washing fluid forced through these openings will result in imparting a rotative movement to the spraying or rinsing devices in a manner known in this art.

The details of the valve generally indicated at 25 are shown in detail in Figs. 4 to 8 inclusive. The structure and operation of this valve is such that the same automatically and at predetermined intervals, directs the washing fluid to pairs of the spraying or rinsing devices 17 of the apparatus in a manner to be explained. The valve 25, as seen in Figs. 1 and 4, is securely attached to the bottom of the housing 10 by means of two bolts 35 which connect the bottom 15 of the housing with the bosses 36 of the valve housing 37. The valve housing 37 is generally tubular in shape, and includes a longitudinally extending cylindrical chamber 38 which is formed with three laterally extending channels disposed at right angles to the chamber 38, as more clearly seen in Fig. 5. The central one of these channels, or that indicated at 39, constitutes a supply conduit. The other two channels, indicated respectively at 40 and 41, constitute discharge passages. The supply channel 39 is directed downwardly and is in communication with a chamber 42 in which a filter or strainer is contained, the same consisting of a body 43 of stainless or non-corrosive metallic wool. The filter body 43 is enclosed in a cylinder 44 having a perforated or foraminous top and bottom. The casing in which the chamber 42 is located is provided around its lower edge with a flange 45 to which is attached a pipe coupling 46 by means of the screws 47 or equivalent fastening elements. The pipe coupling 46 is formed with a part 48 having two passages indicated respectively at 49 and 50, and to which conduits 51 and 52 can be connected from a source of supply for the detergent or washing agent (not shown).

In order to effectively supply the flow of de-

tergent or washing agent through the apparatus, the inner ends of the passages 49 and 50, and which open into the central passage 53 in the pipe coupling 46, are angularly or obliquely directed to be thus with and against the flow of the entering water from the supply pipe 26. In this manner the speed of the entering water is employed to direct the detergent toward the spraying or rinsing devices. The supply pipe 26 from a source of water supply, is attached to the coupling 46, being connected thereto by the nipple 54 and being thus placed in communication with the central passage 53 extending through the coupling 46.

The channel 40 which is located above the axially-extending center line of the valve housing 37, has one end leading through the boss 55 formed on the valve housing 37, the boss 55 being connected to the pipe 21 that extends to one of the lower bearings 20. The opposite end of the channel 40, located in the housing extension 56, is coupled to the pipe 22 that extends to one of the upper bearings 20, as clearly seen in Fig. 1. The channel 41 is located below the axial center line of the housing 37 and one end located in the boss 57 formed on the valve housing 37, said end being connected to the pipe 23 that extends to the second or right-hand lower bearing 20, while the opposite end of the channel 41, located in the housing extension 58, is connected to the pipe 24 that is connected at its opposite end to the left-hand upper bearing 20.

Formed in the valve housing 37 is the chamber 38, which has its opposite ends closed by the closure plugs or caps 60. Said chamber 38 is in communication with the channels 40 and 41 by means of the passages 61 and 62 respectively which extend substantially parallel to the chamber 38. The passage 62 is arranged to be controlled by means of a needle valve, including the spindle 63, adjustable through the gland nut 64 and stuffing box 65, which parts are located in a sleeve 66 formed on and extending from the valve housing 37. One end of a lateral part 67 of the passage 62 constitutes a seat for the tapered or pointed end of the needle valve spindle 63.

Within the chamber 38 are located two two-headed pistons arranged for slidable movement in a manner to be described. One of the pistons generally indicated at 68 may be referred to as the operating piston, and that shown at 69 may be termed the reversing piston. The operating piston 68 includes a spindle or shaft 70, at the opposite ends of which are located the two heads 71 which are held in position on the spindle or shaft by the nuts 72 which hold the heads 71 clamped against shoulders formed on the spindle or shaft 70. A spring 74 is located between each of the heads 71 and a washer 75 which is slidable on the spindle or shaft 70. The sliding movement of the two washers 75 is limited by the reversing piston 69 and by the shoulders 76 formed on the spindle 70. The reversing piston 69 which slides on the spindle 70 and surrounds the spindle, includes two piston heads 77 preferably but not necessarily formed integrally with a central rod section 78.

The piston heads 77 are hollow and at the bottom are formed with a number of apertures 79 constituting ports through these heads. The central rod portion 78 is provided with two spaced annular grooves 80 between which is located an intermediate cylindrical portion or collar 81, each of the grooves 80 being bounded

5

at one side by a conical portion 82. The two grooves 80, the collar 81, and the conical portions 82 cooperate with a locking device, indicated generally at 83 in Fig. 6, and shown in detail in Figs. 7 and 8, to lock the reversing piston in either of two positions, the stroke of the piston being equal to the distance between the two grooves 80.

The locking device 83 shown in Figs. 6 to 8 inclusive, is located in a sleeve 84 formed on and extending angularly or obliquely from the valve housing 37. This locking device includes a locking plunger 85, slideable within the sleeve 84 and spring-pressed toward the rod portion 78 by a coil spring 87 back by the nut 86. The inner end of the locking piston 85 is forked to carry a rotatable roller 89 mounted on the shaft 90 extending across the forked end of the plunger 85.

In its locking positions, the roller 89, acting under the pressure of the coil spring 87, engages in one or the other of the grooves 80 of the piston rod portion 78. In order to minimize friction between the plunger 85 and the sleeve 84 in which it is slidably mounted, and also to prevent the plunger 85 from turning about its longitudinal axis, two balls 91 are supported near the front part of the plunger 85. Grooves fitting the balls are provided in the walls of the sleeve 84. The rear end 92 of the plunger 85 is guided in the recess 93 in the threaded nut or closure plug 86, as clearly seen in Fig. 6.

From the foregoing, the operation of the valve will be readily understood. Reference is made to Figs. 4 and 5 wherein the valve is shown in operating position immediately prior to its reversing movement. The washing fluid enters the valve by passing through the supply pipe 26, thence through the strainer or filter body 43 and into the discharge channel 40, which is at this time opened by being to one side of the left piston head 71, and into the pipes 21 and 22 and to the respective spraying or rinsing devices 17 to which those pipes are connected, namely, the left-hand lower one and the right-hand upper one. The space in chamber 38 between the heads 71 of the operating piston becomes filled with the fluid by passage through the apertures 79 so that pressure on the inside of the operating piston and on the reversing piston is equal. The washing liquid then flows through the nozzles on the rinsing or spraying heads 19 toward the serrated portions 28 of the spinner arms 27 causing rotation of the spiders 18 and rinsing heads 19 carried thereby. This, of course, refers to the left-hand lower spider and the right-hand upper one. Due to the fact that these particular spiders are coupled to their companions by the belts 30, it is obvious that the right-hand lower spider and the left-hand upper one will be caused to rotate or idle but not spray. Due to the resistance exerted in the pipes 21 and 22 and their rinsing or spraying devices 17 respectively, a counter-pressure occurs causing the washing liquid to flow through the passage 61 and into the part of chamber 38 that is located between the left piston head 71 and the adjacent end cap 60 to build up and to exert pressure on the left or closed end of the left piston head 71. In the space between the right piston head 71 and the adjacent end cap 60 of the chamber 38, there is no controlling liquid pressure. As a result, the pressure against the end of the left piston head 71 compresses the spring 74 acting against said piston head while the other spring 74 operative against the right piston head 71 is in its expanded

6

position, resulting in the position of the piston heads 71 shown in Fig. 4, in which position the left head 71 of the reversing piston rests against the inner end of the left piston head 71 of the operating piston. As pressure builds up against the left piston head 71, the reversing piston is finally forced toward the right, and the roller 89 of the locking device is forced out of the right hand groove 80 in the piston rod portion 78, thus releasing the left spring 74 and causing it to move the reversing piston toward the right until the roller 89 of the locking device engages in the left groove 80 of the piston rod portion 78. The discharge channel 41 is now open by movement of the right piston head 71 away from it and the channel 40 is now closed by the left piston head 71. The fluid, now directed through the channel 41 will pass through the pipes 23 and 24, thus setting the upper left-hand spraying or rinsing head and the lower right-hand rinsing or spraying head in operation, while the two other spraying heads will then be rotated but will not spray. The time intervals for operating the respective pairs of spraying or rinsing heads can be controlled by the throttling or needle valve 63 as will be readily apparent.

Due to leakage in the reversing valve above described, some slight variation in operating periods between the two pairs of spraying heads 30 may occur, but this is not of consequence. By reason of such slight variation in operating periods of each pair of spraying heads, the particular position at which each spraying head reverses its direction of rotation tends to shift 35 during operation of the apparatus.

The embodiment of the invention shown in Figs. 9 to 12 is of simpler construction than that just described, its primary difference being that a single piston is employed and the use of springs 40 operative thereon has been eliminated. Movement of the piston is controlled through the pressure of the liquid and a successive opening and closing of the discharge channels is attained. In this embodiment of the invention, 45 the valve housing 100 is attached to the bottom 15 of the casing or housing of the apparatus by means of the tubular or hollow screws 101.

The valve housing 100 is shaped somewhat similarly to the housing 37 previously described, 50 and includes a cylindrical chamber 102 in communication with a liquid-supply passage 103 and four discharge channels indicated respectively at 104, 105, 106 and 107. All of these channels extend laterally from the valve casing 10 and are 55 proper and substantially at right angles thereto and are in the form of bosses formed on and projecting from said housing 100. The two discharge channels 104 and 105 extend upwardly through the bottom 15 of the casing 10 and are connected with both of the upper rinsing or spraying devices 17 by pipes or conduits arranged inside of the casing 10. The two remaining discharge channels 106 and 107 extend horizontally and are connected by pipes or conduits 60 on the outside of the casing 10 to the lower rinsing or spraying heads. The supply channel 103 is directed downwardly and is connected to the liquid-supply pipe 26 as explained with respect to the first embodiment of the invention.

The chamber 102 in the valve housing 100 is closed at both of its ends by means of the threaded closure plugs 109. Each of said plugs is provided with a centrally located recess 110 from which extend radial passages 111 to there- 75 by connect said central recess with an annular

groove 112 formed in the edge of the plug 109. Said annular groove 112 communicates with a channel 113 extending laterally from it, and said channel 113 is controlled by a needle valve 115 to regulate the extent of communication of the channel 113 with a port 114 extending through the fastening screws 101 and being thus in communication with the interior of the housing or casing 10.

Located within the valve chamber 102 is a piston generally indicated at 116, and a valve arrangement extending axially of the piston and generally indicated at 117. The piston consists of two piston heads 118 connected in spaced relationship by a tubular rod 119. Formed in the wall of the tubular rod 119 is an aperture 121 which communicates with the interior of the tubular rod 119 and in the annular space between the inner wall surface of the rod and the valve member generally indicated at 117. Aperture 121 is in communication with the supply passage 103, as will be apparent from Fig. 9.

The valve means indicated generally at 117 includes a solid rod 122 which extends axially through the tubular rod 119, end screws 123, washers 124 and coil springs 125 encircling the rod 122 at its opposite ends. The washers 124 and the edge of the recess 110 of the cover 109 form valve head and seat therefor, respectively.

In Fig. 9 the valve is shown in a position wherein the discharge channels 105 and 107 are open. At this time, the left-hand valve controlled channel, consisting of the elements 110, 111, 112, 113 and 114, is also open since at this time the left valve-washer 124 is away from its seat. It will be noted that the right-hand channel is closed since the right washer 124 is maintained against its seat and thus closes the right aperture 110. Liquid entering the supply passage 103 will pass through the aperture 121 and flow through channel 120 to the chambers located between the outer ends of the pistons 118 and the plugs 109. In the left-hand chamber no liquid pressure occurs since the liquid entering therein will be freely discharged by the valve therein composed of the elements 124 and 119 being open. On the right-hand side of Fig. 9 the valve 124-110 is shut due to the liquid pressure acting to force the washer 124 against the inner end of the aperture 110. As this pressure builds up it will be exerted against the right end of the piston head 116 and soon cause the same to be moved to the left. When this occurs, the left piston head 116 will act to compress the left spring 125 causing it to force the rod 122 and the left washer 124 thereon against the inner end of the aperture 110 and close said aperture. This will bring the right washer 124 away from its seat. Pressure will then begin to build up in the left chamber until it is sufficient to shift the left piston to the right, thereby relieving such pressure and causing a repetition of the cycle above described.

In view of the foregoing, it will now be understood that the hydraulically operated valve structure 25 in Figs. 4 to 8 and similar valve structure in Figs. 9 to 12, act automatically to supply liquid in a definite manner to the rotatable spraying devices 17. In the operating position of valve structure 25 as seen in Figs. 4 and 5, liquid is being supplied to the top right-hand spraying device 17 and bottom left-hand spraying device 17 in Fig. 2A. When the operating piston 68 and reversing piston 69 in Figs. 4 and 5 shift to the right to effect closing of channel

and opening of channel 11, in the manner previously explained, then liquid is supplied for an interval of time to the top left-hand spraying device 17 and bottom right-hand spraying device 17 in Fig. 2A. In this manner successive bodies of liquid delivered through supply conduit 26 are alternately supplied to a particular pair of spraying devices 17, one of which is located at the top and the other at the bottom of the casing or housing 10. In addition, the spraying devices 17 which are active at any particular moment are vertically offset from one another and effective to spray liquid onto different regions of a batch of dishes being cleansed. I have discovered that when the spraying devices 17 are operated in the manner just described, the washing effect is substantially better than when all four spraying devices are operated continuously. This may be due to the fact that the line pressure of the water supply is higher and the efficiency of the apparatus is increased when only two spraying devices 17 are active at a particular moment.

In Fig. 2 are shown the two spraying devices 17 which are mounted for rotation about different axes alongside one another at the bottom of the casing 10. In view of the manner in which the valve structure 25 operates to supply liquid to the spraying devices, at any particular moment liquid is supplied under pressure only to one of the spraying devices in Fig. 2. Hence, when the left-hand spraying device 17 in Fig. 2 is rendered operable to spray liquid against dishes being cleansed, the right-hand spraying device 17 is driven by the belt connection 30 between the spraying devices. While the left-hand spraying device 17 is being hydraulically driven, therefore, the right-hand spraying device is rotating under what might be referred to as a "no-load" condition. In other words, the right-hand spraying device is not effective to spray liquid and incapable of developing any force which will impart rotating movement thereto. Hence, the active left-hand spraying device actually constitutes a driving member and the right-hand spraying device the driven member for the conditions which have been assumed; and in such arrangement the right-hand spraying device essentially acts as a brake and slows down the speed of rotation of the left-hand spraying device. The braking action is due to the friction of the rotatable mounting provisions for each spraying device when it is being driven by the other spraying device which is active and to which liquid is being supplied. I have discovered that the braking action of the non-active spraying device on the active spraying device produces several useful results in that the force at which the individual liquid jets of the active spraying device impinge and strike the dishes being cleansed is increased and the field of action of the individual jets is improved.

In the embodiment of Figs. 1 and 2, for example, the grooves 28 in the arms 27 act to change the direction of the liquid jets which issue horizontally from the jet heads 19, and, after flowing in the grooves, are deflected vertically upward in a multiplicity of different directions depending upon the angular extent of curvature of the individual grooves. As seen in Fig. 1, the outer peripheral extremity of certain grooves extend vertically upward a greater distance than other grooves, thus producing spaced apart peak points and valleys therebetween.

The vertically directed component of force at which the deflected jets leave the grooves 28 in arms 27 is dependent on the difference between the angular velocity at which the jets issue from a nozzle head 19 and the angular velocity of the grooves 28 which in turn is dependent upon the angular velocity of the radially extending arms 27. When the difference between the angular velocity of the jets issuing from a nozzle head 19 and angular velocity of the arms 27 is relatively small, the vertical component of the force at which the deflected jets leave the grooves 28 is relatively small. However, when the difference between the angular velocity of the jets issuing from a nozzle head 19 and the angular velocity of the arms 27 is relatively great, the vertical force component imparted to the deflected jets passing from the grooves 28 also will be relatively great. Hence, the breaking action of the driven sprayer on the active sprayer slows down the speed of rotation of the arms 27 of the latter, so that the difference in angular velocity between the jets issuing from a jet head 19 and arms 27 will be increased and thereby increase the vertical component of force imparted to the deflected jets leaving the grooves 28.

Also, since liquid is supplied intermittently to the different spraying devices 17 by the operation of the valve structure 25, the spraying devices do not rotate continuously at a single constant speed but tend to decelerate at the moment the supply of liquid is being shifted and tend to accelerate after the shift is completed. Hence, the spraying heads 19 rotate at a speed which fluctuates, thereby causing variations in the difference between the angular velocity of the jets issuing from the jet heads 19 and angular velocity of the arms 27 which in turn results in variations in the vertical component of force imparted to the deflected jets passing from the grooves. This also results in producing jets which act in a greater number of directions and in effect increases the field of action of the jets.

This increase in the field of action of the jets, due to variations in speed of the spraying devices, perhaps may be brought out more clearly by explaining what happens when it is assumed the arms 27 remain stationary which will also be true of the grooves 28 formed in the arms. In such case the jets deflected by the grooves will issue from the latter in a direction coinciding with the plane of the groove at its outlet end. Now, if the arms 27 are allowed to turn and rotate, certain movement will be imparted to the jets while being deflected during their passage through the grooves. This additional movement imparted to the jets in effect adds a tangential component to the movement of the jets which is dependent solely upon the direction of the groove, and in such case the jets will issue in what may be referred to as an "obliquely forward" direction.

If the arms 27 rotated at a steady speed, the tangential component of movement imparted to the deflected jets would always be of the same magnitude and the jets would always be deflected the same extent or degree in an "obliquely forward" direction. By providing an arrangement in which the arms 27 alternately accelerate and decelerate and do not turn at a steady and uniform speed, the magnitude of the tangential component of force imparted to the jets being deflected in the grooves 28 will also vary, wherefore the extent to which the jets shift in an obliquely forward direction will always be shift-

ing. In this way the deflected jets will issue from the grooves in a great number of directions and be effective in a wide field of action.

In Fig. 2 the spraying device 17 which is active rotates in a clockwise direction while the driven or inactive spraying device rotates in a counter-clockwise direction by reason of the fact that the belt connection 30 therebetween is crossed. In the embodiment of Fig. 3, the left-hand spraying device 32 when active imparts clockwise movement to the arms 31 while the right-hand spraying device 32 when active imparts counter-clockwise movement to the arms 31 associated therewith. Since the belt connection 30 in Fig. 15 is not crossed as in Fig. 2, each spraying device 32 when inactive and driven by the other spraying device will rotate in the same direction as the spraying device acting as the driving member.

In both Figs. 2 and 3, however, a rapid deceleration of the active spraying device occurs when the supply of liquid thereto is cut off due to the braking action of the other spraying device. In each embodiment the hydraulically operated valve structure begins to supply liquid to the liquid directing members 27 and 31, respectively, of the spraying devices which are about to resume operation even before such spraying devices cease to be driven by the belt connections 30 in a direction which is opposite to the direction that the hydraulically developed forces act to initiate turning movement of the spraying devices. With such an arrangement, liquid jets having a relatively great impact force issue from the spraying devices.

Having described several embodiments of the invention, it is obvious that the same is not to be restricted thereto, but is broad enough to cover all structures within the scope of the annexed claims.

What is claimed is:

1. In dishwashing apparatus, a group of spaced apart spraying devices, means for mounting said spraying devices for rotatable movement about different axes, each of said spraying devices being operable as a driving means and active to spray liquid when liquid is supplied thereto, connections including control means for supplying liquid to said spraying devices, means for mechanically coupling said rotatable spraying devices whereby, when one part thereof in the group becomes active and operable as a driving means, said one part will impart movement to another part in the group which is inactive and becomes a driven means, mechanism operatively connected with said control means to cause the latter to supply liquid intermittently to each spraying device, said control means including said mechanism being constructed and arranged to render each spraying device active to spray liquid and becomes operable as a driving means for one interval of time and to render each spraying device inactive to spray liquid and become a driven means for another interval of time, each movable spraying device in the group, when inactive and becoming a driven means, being effective to develop a braking action on the part of the group which is operable as a driving means.
2. Apparatus as set forth in claim 1 in which the direction of movement of each spraying device and means for mechanically coupling said movable spraying devices are so inter-related that, when said control means including said mechanism becomes operable to terminate the

supply of liquid to one spraying device and start the supply of liquid to another spraying device which up to the moment has been inactive and a part of the driven means, the spraying device to which the supply of liquid is being started will offer maximum resistance to its development as a driving means for the group of spraying devices.

3. Apparatus as set forth in claim 1 in which said control means including said mechanism associated therewith is so constructed and arranged that the supply of liquid to one spraying device, which has been inactive and a part of the driven means, is started while movement is still being imparted thereto by another of the spraying devices which up to the moment has been active and operable as a driving means.

4. Apparatus as set forth in claim 1 in which said control means including said mechanism is constructed and arranged to terminate the supply of liquid to one spraying device and commence the supply of liquid to another spraying device substantially instantaneously.

5. In dishwashing apparatus, a pair of spaced apart spraying devices, means for mounting said spraying devices for rotation about different axes, each of said spraying devices becoming active to spray liquid and embodying means operable to effect positive rotation thereof responsive to the pressure of the liquid supplied thereto, a supply line including control means for supplying liquid to said spraying devices, said control means embodying provisions to cause the latter to supply liquid alternately to said spraying devices, each spraying device alternately being active to spray liquid and be positively rotated when liquid is being supplied thereto and then inactive to spray liquid when the supply of liquid thereto is cut off; and means connecting said rotatable spraying devices to render each spraying device when active operable to drive and rotate the inactive spraying device which then becomes a driven rotatable means, each spraying device, when inactive and becoming a driven rotatable means, being effective to develop a braking action on the active spraying device.

6. Dishwashing apparatus comprising a casing having a front access opening and closure means therefor; two pairs of rotatable spraying devices of the kind specified in claim 5, one pair of said spraying devices being disposed at the vicinity of the top of said casing and the other pair being disposed at the vicinity of the bottom of said casing, the spraying devices of each pair being offset laterally with respect to one another, said control means being so constructed and arranged that the spraying devices at the top and bottom of said casing which are active at a given moment are always offset vertically from one another.

7. Dishwashing apparatus as set forth in claim 5 in which said rotatable spraying devices are so constructed and arranged that both rotate in the same direction when liquid under pressure is alternately supplied to the spraying devices, and said connecting means being so constructed and arranged that, when each rotatable spraying device becomes active and positively rotated in one direction when liquid is being supplied thereto, the other spraying device which is inactive to spray liquid is driven in the opposite direction from said active spraying device.

8. Dishwashing apparatus as set forth in claim 5 in which said rotatable spraying devices are constructed and arranged that one device

rotates in one direction and the other rotates in the opposite direction when liquid under pressure is alternately supplied to the spraying devices, and said connecting means being so constructed and arranged that, when each rotatable spraying device becomes active and positively rotated in one direction when liquid is being supplied thereto, the other spraying device which is inactive to spray liquid is driven in the same direction as said active spraying device.

9. In dishwashing apparatus, a casing having an access opening in a side wall thereof and closure means therefor, a first pair of rotatable spraying devices at the vicinity of the top of said casing, a second pair of rotatable spraying devices at the vicinity of the bottom of said casing, each of said rotatable spraying devices becoming active to spray liquid and embodying means operable to effect positive rotation thereof responsive to supply of liquid thereto under pressure, the spraying devices of each pair being laterally offset with respect to one another, a supply line including hydraulically operated control means to supply liquid alternately to the spraying devices in each pair, each spraying device of a pair alternately being active to spray liquid and be positively rotated when liquid is being supplied thereto and then inactive to spray liquid when the supply of liquid thereto is cut off, and belt means connecting each pair of rotatable spraying devices at the top and bottom, respectively, of said casing, each spraying device when inactive becoming a driven rotatable means which is effective to promote a braking action on the active spraying device connected thereto by said belt means.

10. Dishwashing apparatus as set forth in claim 9 in which each spraying device at the bottom of said casing is essentially beneath one of the spraying devices at the top of said casing, said hydraulically operated control means being so constructed and arranged that the spraying devices at the top and bottom of said casing which are active at a given moment are always offset laterally from one another.

11. In dishwashing apparatus, a pair of spaced apart spraying devices, means for mounting said spraying devices for rotation about different axes, each of said spraying devices becoming active to spray liquid and embodying means to effect positive rotation thereof responsive to supply of liquid thereto under pressure, a supply line including hydraulically operated control structure for supplying liquid to said spraying devices, said control structure having a plurality of outlet channels each of which is in communication with one of said spraying devices, said control structure being operable responsive to liquid under pressure to cause liquid to be supplied alternately to said

12. spraying devices, each spraying device alternately being active to spray liquid and be positively rotated when liquid is being supplied thereto and then inactive to spray liquid when the supply of liquid thereto is cut off, and means connecting said rotatable spraying devices to render each spraying device when active operable to drive and rotate the inactive spraying device which then becomes a driven rotatable means, each spraying device, when inactive and becoming a driven rotatable means, being effective to develop a braking action on the active spraying device.

JOHAN FREDRIK ROBERT KARLSTROM.
